UNITED STATES PATENT OFFICE.

JOSEPH M. WOODS AND FREDERICK E. M. GIESEBRECHT, OF CHICAGO, ILLINOIS.

WHEEL-FLANGE LUBRICATOR.

1,110,276.

Specification of Letters Patent.

Patented Sept. 8, 1914.

Application filed June 6, 1913. Serial No. 772,036.

To all whom it may concern:

Be it known that I, JOSEPH M. WOODS, a citizen of the United States, and FREDERICK E. M. GIESEBRECHT, a subject of the Emperor of Germany, both residing at Chicago, Illinois, have invented certain new and useful Improvements in Wheel-Flange Lubricators, of which the following is a specification.

10 The essential object of this invention is to provide a simple and convenient means for applying lubricant between the flange of a car wheel and the side of the tread of the rail upon which the wheel is riding, and the lubricant is intended to be applied at such times as the car is rounding a curve, or otherwise producing a grinding upon the rails.

As is well known, the rails forming the 20 track are ordinarily so gaged that the inner edge of the rail tread is about one-half inch from the flange of the wheel; but when the track is curved the wheel on the outer side will have its flange pressed tightly against the rail, while the wheel on the opposite or 25 inner side of the curve will have its flange about an inch from the tread of the rail.

The essential object of the invention is to apply a sufficient quantity of oil, grease, or 30 other lubricant, between the flange of the wheel riding upon the outer rail of the track and the rail itself. The term "outer" is used to designate that rail of the track having the larger radius, whereas the term 35 "inner" designates the rail having the smaller radius.

Although the invention is designed for use primarily to operate at curves, it will also operate under other circumstances 40 where the wheels grind upon the rails, whether because of unevenness in the track or roadbed, or other similar causes.

In the drawings Figure 1 is an end elevation of a pair of wheels to which the invention is applied, the rails and a part of one wheel being shown in section; Fig. 2 is a top plan view looking downwardly from above, Fig. 1; Fig. 3 is a detailed sectional view showing the oil cup or grease cup applied in a different position from that depicted in Fig. 1; Fig. 4 is a sectional view of one of the grease cups; Fig. 5 is a view partly in section and partly in elevation, of a slightly modified form of grease cup; Fig. 55 6 is a top plan view of one of the grease cups looking downwardly in Fig. 4; Fig. 7

is a top plan view looking downwardly in Fig. 5; and Fig. 8 is a view showing the grease cup applied to the body of the car instead of being applied to the wheel or to the 60 axle as depicted in the other figures.

The rails upon which the wheels 1 are adapted to travel are provided with the customary flange 2, web 3, and tread 4, and the wheel itself has the ordinary tire or 65 riding surface 5 and flange 6. As best shown in Figs. 1 and 3, the wheel is provided with a perforation or perforations 7, which are so disposed that when the perforation is in its lowermost position, its 70 axis will be at an angle of approximately 45 degrees to the perpendicular; through each perforation 7 the nipple 8 projects, the construction of which is best shown in Fig. 4.

75 The cup 9, which is adapted to contain the oil or grease, may be secured by a bracket 10 to the axle 11 (Figs. 1 and 6), or it may be bolted or otherwise secured to the wheel itself (Figs. 3 and 7). In this last-mentioned construction the grease cup 9 carries ears 12 perforated at 13, and bolts 14 pass through said perforations 13 and into the tire 5 or spoke 15 or both. Extending from the grease cup 9 to the nipple 8 is a 80 pipe or tube 16. The grease cup is perforated at 17 and the threaded stud 18 projects from the cup 9; the tube 16 is secured to the threaded boss 18 by the union coupling 20. In a similar and obvious manner (Fig. 90 4) the union coupling 21 secures the opposite end of tube 16 to the nipple 8.

Within the nipple 8 (Fig. 4) the plunger 22 is retained, one end of said plunger being adapted to extend beyond the mouth of 95 said nipple 8 for a short distance, as best shown in Figs. 4 and 5. The plunger 22 contains a longitudinal perforation 23 and another perforation or perforations 24 which are in connection with the perforation 23; the plunger 22 carries the beveled head 25, which fits against the seat 26 formed within the nipple 8. The plunger head 25 is received within the cavity 27, which cavity is somewhat larger in diameter than the cylindrical opening 29 within which the main part of the plunger 22 is adapted to slide. When the plunger 22 is forced toward the right (Fig. 4) the openings or conduits 24 ride beyond the seat 110 29 and thus the lubricant within the chamber 27 is permitted to pass through the con-

duits 23 and 24, thus to escape at the left end (Fig. 4) of the plunger 22; but when the parts are as shown in Fig. 4, the conduits 24 are sealed by the walls of the nipple 8 and no lubricant can escape from or pass out of the device when the parts are in that position.

Within the cup 9 is a piston-like head 30, provided with a central aperture 31; said aperture 31 is normally closed by a valve 32 pivoted to the head 30 at 33. The top 34 carries a bolt 35 pivoted to the main body of the cup; a butterfly nut 36 adapted to screw upon the bolt 35 holds the cover 34 closed and the helical spring 37 which is interposed between the under surface of the cover 34 and the piston-head 30, normally presses said piston-head 30 toward the discharge opening 17. When the wheels are riding upon a straight and level stretch of track, the plunger 22 will remain out of engagement with the rails because said plunger 22 projects only a fraction of an inch beyond the flange of the wheel; but whenever the wheel grinds upon the rails, whether because of the rounding of a curve, or for other reason, the plunger 22 will strike the rail tread each time that the nipple 8 comes opposite to the tread; thereupon the rail tread will press the plunger 22 toward the right (Fig. 4); a quantity of the lubricant contained within the diameter 27 will thus be expressed through the conduits 23 and 24 and will go between the flange of the wheel and the rail tread. Since the helical spring 37 is constantly pressing the piston-head 30 toward the discharge end, the lubricant will thus be constantly pressed through the tube or pipe 16 and toward the nipple 8; and since the lubricant will thus at all times be retained under pressure within the chamber 27, the lubricant will press upon the beveled head 25, thus normally tending to force the plunger to the position of Fig. 4. As the wheel revolves upon the track and whenever it grinds upon the rail, the rail will force the plunger 22 toward the right (Fig. 4) thus permitting a small quantity of lubricant to enter the conduits within the plunger, and almost instantaneously after the left-to-right movement of the plunger caused by the rail, the pressure of the lubricant within the apparatus will force the plunger back from right to left, thus sealing the mouths of the conduits 24 and preventing the further escape or passage of the lubricant from the apparatus.

In Fig. 8 another modification is shown. This form of the invention provides a grease cup 9 rigidly secured by straps 40 to the car itself, preferably to the body bolster. The pipe or tube 16 is so arranged that the exposed end of the plunger 22 is presented to the flange of the wheel. Whenever the

flange strikes the plunger, it will force same inwardly and the operation of the device will be the same as with the preferred forms of the invention, the only difference between the form depicted in Fig. 8 and the other forms being that in one case it is the flange of the wheel which strikes and actuates the plunger, whereas in the other forms, it is the rail itself.

In order to fill the cup 9 with lubricant after the supply has run low or become exhausted, the nut 36 is turned so as to permit the opening of the cover 34; when the cover 34 has been swung upon pivot 41 as a hinge, the valve 32 may be opened and a fresh supply of lubricant inserted through the port 31.

It is obvious that many changes in the construction and arrangement of parts may be made without departing from the scope of the invention or of the various claims.

We claim as our invention:

1. A lubricating apparatus, comprising a cup to store the lubricant, a pipe or tube extending therefrom, a nipple in connection with the said pipe, said nipple terminating at a point adjacent the crotch formed between the tire and the flange of a wheel, and a plunger within the nipple, said plunger being provided with a conduit through which the lubricant is adapted to pass, one end of said conduit being normally closed by the wall of the nipple, said plunger being adapted to be unseated upon engagement with the rail, and means for applying pressure upon the lubricant retained within the apparatus.

2. A lubricating apparatus, comprising a cup to store the lubricant, a pipe or tube extending therefrom, a nipple in connection with said pipe, said nipple terminating at a point adjacent the crotch formed between the tire and the flange of a wheel, and a plunger within the nipple, said plunger being provided with a conduit through which the lubricant is adapted to pass, one end of said conduit being normally closed by the wall of the nipple, said nipple being formed with a beveled seat and said plunger being provided with a beveled head adapted to cooperate with said seat, said plunger being provided with a conduit, one mouth of which is normally closed by the wall of the nipple, said mouth being adapted to be exposed when said head is forced off said seat, and means for applying pressure upon the lubricant which is retained within the apparatus.

3. A lubricating apparatus, comprising a cup to store the lubricant, a pipe or tube extending therefrom, a nipple in connection with said pipe, the discharge end of said nipple being closely adjacent the flange of the wheel, said nipple being provided with two interior chambers of unequal diameters, a plunger provided with a conduit through

which the lubricant is adapted to pass, the main body of said plunger being received within the chamber of smaller diameter, and one end of said conduit being adapted to be normally closed by the wall of said chamber, a head upon said plunger received within the larger of said chambers, means for forcing lubricant under pressure from said cup and into the larger of said chambers, and means for forcing the plunger inwardly into said nipple to a point where said nor-

mally-closed conduit end will be in connection with the larger of said chambers.

In testimony whereof we hereunto affix our signatures in the presence of two witnesses.
